UNITED STATES PATENT OFFICE

162,916

ELECTRIC SPACE HEATER

William W. Wittie, Chicago, Ill.

Application October 8, 1949, Serial No. 5,383

Term of patent 3½ years

(Cl. D81—10)

To all whom it may concern:

Be it known that I, William W. Wittie, a citizen of the United States, residing at city of Chicago, county of Cook and State of Illinois, have invented a new, original, and ornamental Design for an Electric Space Heater, of which the following is a specification, reference being had to the accompanying drawing, forming a part hereof.

Figure 1 is a top plan view;

Figure 2 is a front view;

Figure 3 is a side view, partially in cross section to show shape of front panel; and

Figure 4 is a rear view of an electric space heater embodying my new design.

I claim:

The ornamental design for an electric space heater as shown.

WILLIAM W. WITTIE.
